Attorney.

UNITED STATES PATENT OFFICE.

ARON B. BLAUSTEIN, OF NEW YORK, N. Y.

CLOTHES-HANGER.

1,318,257.

Specification of Letters Patent.

Patented Oct. 7, 1919.

Application filed June 17, 1919. Serial No. 304,852.

To all whom it may concern:

Be it known that I, ARON B. BLAUSTEIN, a citizen of the United States, and residing at New York, Bronx county, New York 5 State, have invented certain new and useful Improvements in Clothes-Hangers, of which the following is a specification.

This invention relates to clothes hangers and especially to light articles of clothing 10 such as shirt waists which are adapted to be hung in quantities upon each other so that economy in space may result. In accomplishing this result the present invention comprises a bracket with a plurality of 15 hooks and adapted to be dropped to a horizontal position where it is suspended and loaded with the desired number of garments that are hung on the hooks, then the bracket is elevated into a vertical position where it 20 is retained by a suitable catch when the garments will lie against the wall upon each other. These and other objects and details of the invention are more fully described in the following specification, set forth in 25 the appended claims and illustrated in the accompanying drawings, wherein:

Figure 1 is a perspective view of the improved hanger suspended for loading.

Fig. 2 is a side view of the hanger with 30 the bracket elevated and retained.

The device is mounted on a vertical bar 5 which may be secured permanently in a closet or on a wall and has secured to its outer face a frame 6 U-shaped in cross 35 section with a fastening hook 7 at its upper end and within the channel of the frame is a guideway 8 open at one side to receive the end 9 of a suspending rod 10 and allow it to play therein but be retained by appropriate means, such as an enlarged head and 40 the closed bottom of the guideway 8.

To the lower end of the frame 6 is carried a swinging frame 11 of almost identical shape and size as the frame 6 but slightly 45 wider to fit about the sides of the stationary frame when folded up as shown in Fig. 2.

The outer end of the suspending rod 10 is hooked beneath a strap 12 on the inner side of the frame 11 and hinged so that when 50 the latter is elevated the end 9 of the rod 10 will slide up the interior of the guideway

8 and the rod will be inclosed and out of sight.

The hook 7 is closed down and retained by friction or by a spring to hold the frame 55 11 in the upright and closed position but the leverage of the lower end affords a ready means for releasing the frames.

On the lower side of the frame 11 are a series of hooks 13 on which may be hung 60 coat racks carrying the garments to be hung, and the number and size of the same may vary as the occasion demands.

After the desired number of garments are hung on the hooks 13 the frame 11 is swung 65 into the vertical position and the garments drop upon each other and occupy a very limited amount of space in the closet or apartment.

It is obvious that the parts may be otherwise arranged or modified without departing from the essential features above described or from the scope of the appended claims.

What I claim as new is:

1. In clothes hangers, the combination of 75 a box-shaped member adapted to be secured vertically, a second box-shaped member adapted to swing on and inclose the first member and having hooks, and a suspending rod connecting the members and adapted to slide and fold in the two members.

2. In clothes hangers, the combination of 80 a rigid vertical member having a slide, a second member pivoted to and adapted to envelop the first member, hooks on the latter member, and a supporting rod pivoted to the second member with one end and whose other end operates in the slide.

3. In clothes hangers, the combination of 85 a base board, a channeled frame on the board, a second channeled frame pivoted to the lower end of the first frame, a suspending rod hinged at one end to the pivoted frame and whose other end slides in a guideway on the first frame, a pivoted catch at the upper end of the first frame to secure the other frame, and hooks on the outer and lower side of the pivoted frame.

4. In clothes hangers, the combination of 90 100 a vertical base board, a channeled frame secured to the board, a second channeled

frame pivoted to and adapted to fold on the first frame, a guideway in the first frame, a suspending rod hinged at one end to the pivoted frame and whose other end slides 5 in the guideway, a pivoted catch on the first frame to secure the second when folded, and hooks on the outer and lower side of the pivoted frame.

In testimony whereof, I have signed my name to this specification in the presence of 10 two subscribing witnesses, this 16th day of June, 1919.

ARON B. BLAUSTEIN.

Witnesses:

JAMES F. DUHAMEL,
WALTER E. McDONNELL.
